UNITED STATES PATENT OFFICE

164,296

COMBINATION ASH TRAY AND COASTER

Frank E. Gillespie, Jr., Jamaica Plain, Mass.

Application September 1, 1950, Serial No. 12,027

Term of patent 7 years

(Cl. D85—2)

To all whom it may concern:

Be it known that I, Frank E. Gillespie, Jr., a citizen of the United States, residing at Jamaica Plain, in the county of Suffolk and State of Massachusetts, have invented a new, original, and ornamental Design for a Combination Ash Tray and Coaster, of which the following is a specification, reference being had to the accompanying drawings, forming a part thereof.

Figure 1 is a top plan view of the combination ash tray and coaster, showing my new design;

Figure 2 is a side elevational view; and

Figure 3 is a transverse sectional view taken on line 3—3 of Figure 1.

I claim:

The ornamental design for a combination ash tray and coaster, as shown.

FRANK E. GILLESPIE, JR.
